UNITED STATES PATENT OFFICE.

FLORENT HINNEKENS, OF PATERSON, NEW JERSEY.

TENTERING-CLIP.

1,339,509.

Specification of Letters Patent. Patented May 11, 1920.

Application filed April 17, 1919. Serial No. 290,805.

To all whom it may concern:

Be it known that I, FLORENT HINNEKENS, a citizen of the United States, residing at Paterson, in the county of Passaic and State 5 of New Jersey, have invented certain new and useful Improvements in Tentering-Clips, of which the following is a specification.

This invention relates to tentering clips 10 for tentering machines, and it has for its object to improve the construction of these devices particularly with a view (1) to make them operate successfully on and without injury to the most delicate fabrics, (2) to insure perfect coaction of the grip lever and the feeler-lever, and in the open position obtain certain and ample clearance for the entry of the edge of the fabric, (3) to obtain adjustments of the feeler-lever so 15 as to modify the action thereof to suit fabrics of different grades of resistance to its pressure, and (4) to cause the grip levers, *per se*, to operate to best advantage. To these ends the improved clip includes, with 20 a bifurcated body having a fabric-gripping table at the inner side of one arm, a grip-lever fulcrumed in the other arm and movable against the table to coact therewith to grip the fabric, the table having an aperture 25 past which the grip-lever moves to gripping position, a feeler-lever fulcrumed between its ends in the body on an axis parallel with that of the grip-lever and having its forward or feeler end enterable into said aperture 30 and its rear end portion a weight and normally adapted to hold the feeler end elevated, the grip-lever having means to bear on the feeler arm of the feeler-lever to press it downward to detecting position and the 35 feeler-lever preferably having an overhang or hook to overlie said means when depressed and thereby insure the rise of the feeler-lever when the grip-lever opens. The feeler-lever is further, in the preferred 40 form, arranged so that its position may be adjusted toward or from the grip-lever. Also, the grip-lever has its upstanding actuating arm arranged at such an angle that in the closed position its weight tends to 45 hold the grip-lever against the table and in the open position is neutral.

In the drawings,

Figure 1 shows in plan a fragment of a "chain" of the improved clips;

55 Fig. 2 is a front elevation of one of the clips; and

Figs. 3, 4 and 5 show the clip in side elevation, in open, closing and closed position, respectively.

The body *a* of the clip is bifurcated in the usual way and forms rigid lower and upper horizontal arms *b*, *c*, being provided with lateral projections *d* which with their pivot pins *d'* form couplings between such clip and neighboring clips in a series of them forming a chain; it may be remarked that my invention relates to that class of clip which as a link or unit of one of two endless chains at opposite edges of the fabric moves at one point of its travel toward the fabric in order to receive its edge and thereupon grip the same and at another point moves relatively outward or away from the fabric so as to stretch the same transversely.

On the arm *b* of the clip is arranged a plate *e* forming a fixed horizontal table, the same being provided with a narrow slot *f* extending longitudinally of the arm *b*. Adapted to coact with the plate *e* in gripping the fabric relatively outward of the slot *f* is a grip-lever *g* which is fulcrumed on a horizontal pin *h* in the end of the arm *c*; the acting edge of this grip-lever (which and the table *e* are preferably as wide as possible without permitting interference between adjoining grip levers) is beveled to a knife edge for its full length, excepting at the points as *i* in Fig. 2, where notches are shown formed therein, so that it will obtain a good grip on the fabric in coaction with the table *e*. To insure perfect parallelism between the table and said edge of the grip-lever, it is preferred to form the arm *c* as a fork when seen in plan (Fig. 1) and space its member as far apart as practicable, the bearing portions *g'* of the grip-lever being each arranged outside of the bearing portions formed by said members of the forked arm *c*; the importance of constructing the clip so that the grip-lever 90 will be and remain in true parallel relation to the table will be apparent when it is remarked that the clip is primarily intended for use in stretching extremely thin fabrics. The gripping lever has a long bifurcated 100 arm *j* projecting rearwardly therefrom, centrally thereof, the branches of this arm being connected at their ends by a pin *k* parallel with the pivoting pin *h*.

An inverted U-shaped bracket *l* is secured 110 to and depends from the arm *c* opposite the arm *j* of the grip-lever; this bracket has

two or more holes *m* to receive a cotter pin *n*, the holes *m* being in a horizontal series and each parallel with the pin *h*. On the pin *n* is fulcrumed a feeler-lever *p* confined by the bracket *l* to move in a vertical plane directly opposite the space between the members of the forked arm *j* of the grip-lever and having a forward arm *p'* which underlies the pin *h* and may enter the said space in the arm *j* and has its free end adapted to enter the slot *f* in plate *e*. The other arm *p''* of the lever is preferably a weight which tends normally to keep the lever in the position shown in Fig. 3, that is, with its arm *p'* elevated. It will be apparent that the grip lever and feeler-lever being in the position shown in Fig. 3, if the grip-lever is moved to gripping position it will engage by its pin *h* the arm *p'* of the feeler-lever and depress the same, and that when the grip-lever is moved in the reverse direction the feeler-lever will return to its normal position; in order to make the return movement of the feeler-lever certain, notwithstanding possible interference therewith of the fabric, the feeler-lever is provided with an overhanging hook *g* which when the grip lever and feeler-lever are fully depressed overreaches the pin *h*. The limit of return movement of the feeler-lever may be afforded by contact thereof with the bracket *l*, as shown in Fig. 3.

The grip-lever has an upstanding arm *g''* adapted to be engaged by well-known means acting to swing back the grip-lever out of gripping relation to the fabric and hold it retracted until the edge of the fabric having been received by the clip, the grip-lever is to return and grip the fabric, the said arm being substantially the same as in other clips of well-known type excepting that in the present case it is canted to such an angle with reference to the grip-lever that when the latter is fully open the arm *g''* stands almost perpendicular and its weight is substantially neutralized so far as any tendency to move the grip-lever is concerned, but when the grip-lever is in gripping position the weight of *g''* becomes a material factor in holding the grip-lever in said position.

In view of the foregoing it will be apparent that the improved clip in the open position (Fig. 3) affords ample clearance in entering the fabric edge; that although the fabrics to be stretched are of the most delicate character, when the grip-lever has been allowed (by the appropriate instrumentality operating on its arm *g''*) to descend toward the gripping position and so depress the arm *p'* of the feeler-lever against the fabric, the pressure of the parts on the fabric while underlying the end of the feeler-lever (Fig. 4) is exceedingly light, because the pin *h* is well removed from the grip-lever and engages the feeler-lever more or less near the

latter's fulcrum (*n*); and that, though the pressure on the fabric is thus exceedingly light, as soon as the fabric recedes from beneath the feeler-lever (Fig. 5), due also to the contact of *h* with the feeler-lever being near the fulcrum *n* thereof, the closing action is quick and certain. When the grip-lever is fully closed its grip is positive and equal throughout its whole width. When the grip-lever is moved to open position by the aforesaid instrumentality the feeler-lever of its own weight moves correspondingly to the open position, though if it should tend to remain down through possible interference with the fabric its rise will be assured by the pin *h* on the grip-lever bearing upwardly against hook *g*.

In order to adjust the action of the parts to suit fabrics varying in ability to resist the tendency of the feeler-lever to press the material into the slot *f* of the plate pin *n* may be shifted from one to the other of the holes *m*.

Having thus fully described my invention, what I claim as new and desire to secure by Letters Patent is:—

1. In combination, with a bifurcated body having a fabric gripping table at the inner side of one arm thereof, a grip-lever fulcrumed in the other arm of said body on a transverse axis parallel with the table and movable into and out of gripping relation with the latter, and a feeler-lever fulcrumed relatively back of the grip-lever on an axis parallel with the axis of the grip-lever and having a forwardly projecting arm, said feeler-lever being normally held with its said arm elevated and the grip-lever having means overlying said arm of the feeler-lever and adapted to depress the same against the fabric overlying the table.

2. In combination, with a bifurcated body having a fabric gripping table at the inner side of one arm thereof, a grip-lever fulcrumed in the other arm of said body on a transverse axis parallel with the table and movable into and out of gripping relation with the latter, and a feeler-lever fulcrumed relatively back of the grip-lever on an axis parallel with the axis of the grip-lever and having a forwardly projecting arm, said feeler-lever being normally held with its said arm elevated and the grip-lever having means overlying said arm of the feeler-lever and adapted to depress the same against the fabric overlying the table, and said feeler-lever also having a forwardly projecting hook overreaching said means when the feeler-lever is held depressed thereby.

3. In combination, with a bifurcated body having a fabric gripping table at the inner side of one arm thereof, a grip-lever fulcrumed in the other arm of said body on a transverse axis parallel with the table and

movable into and out of gripping relation with the latter, and a feeler-lever fulcrumed between its ends relatively back of the grip-lever on an axis parallel with the axis of 5 the grip-lever and having a forwardly projecting arm and a rearward weight-arm, said feeler-lever being normally held by its weight-arm with its said forwardly projecting arm elevated and the grip-lever having 10 means overlying said forwardly projecting arm of the feeler-lever and adapted to depress the same against the fabric overlying the table.

4. In combination, with a bifurcated body 15 having a fabric gripping table at the inner side of one arm thereof, a grip-lever fulcrumed in the other arm of said body on a transverse axis parallel with the table and movable into and out of gripping relation 20 with the latter, and a feeler-lever fulcrumed relatively back of the grip-lever on an axis parallel with the axis of the grip-lever and having a forwardly projecting arm, said feeler-lever being normally held with its 25 said arm elevated and adapted to be depressed by said arm of the grip-lever on movement of the latter to gripping position.

said arm elevated and its axis being shift- 25 able toward and from the grip-lever and the grip-lever having means overlying said arm of the feeler-lever and adapted to depress the same against the fabric overlying the 30 table.

5. In combination, with a bifurcated body having a fabric gripping table at the inner side of one arm thereof, a grip-lever fulcrumed in the other arm of said body on a transverse axis parallel with the table and 35 movable into and out of gripping relation to the latter, and having a rearwardly projecting arm, and a feeler-lever fulcrumed relatively back of the grip-lever on an axis 40 parallel with the axis of the grip-lever and having a forwardly projecting arm underlying the arm of the grip-lever, said feeler-lever being normally held with its said arm elevated and adapted to be depressed by said 45 arm of the grip-lever on movement of the latter to gripping position.

In testimony whereof I affix my signature.
FLORENT HINNEKENS.
